COMBINED SKEWER SET AND CUTTING BOARD

Robert E. Kritkausky, Fort Wayne, Ind., assignor to
K & S Corporation, Fort Wayne, Ind.

Filed Apr. 17, 1972, Ser. No. 245,027

Term of patent 14 years

Int. Cl. D7—04

U.S. Cl. D7—46

FIG. 1 is a top perspective view of a combined skewer set and cutting board showing my new design, one of the skewers being in an exploded position;

FIG. 2 is a side view of a skewer showing my new design;

FIG. 3 is a front view of the skewer illustrated in FIG. 2;

FIG. 4 is a top plan view thereof, the skewers being removed for convenience of illustration;

FIG. 5 is a sectional view of the board illustrated in FIG. 4 taken substantially along the section line 5-5;

FIG. 6 is a sectional view of the board illustrated in FIG. 4 taken substantially along the section line 6-6;

FIG. 7 is a sectional view of the board illustrated in FIG. 4 taken substantially along the section line 7-7;

FIG. 8 is a sectional view of the board illustrated in FIG. 4 taken substantially along the section line 8-8;

FIG. 9 is a sectional view of the board illustrated in

FIG. 4 taken substantially along the section line 9-9;

FIG. 10 is a sectional view of the board illustrated in FIG. 4 taken substantially along the section line 10-10; and

FIG. 11 is a bottom view of the board illustrated in FIG. 4.

I claim:

The ornamental design for a combined skewer set and cutting board, as shown and described.
